MULTIPLE CYLINDER TANK CAR

Harry D. Edwards, Larchmont, N. Y., assignor, by
mesne assignments, to Union Carbide and
Carbon Corporation, a corporation of New
York

Application April 1, 1931, Serial No. 526,974

10 Claims. (CL. 105—360)

This invention relates to a multiple cylinder tank vehicle as for example a railroad car, and has particular reference to a car carrying a plurality of cylinders of the type used as containers 5 for compressed fluids, for example, oxygen.

In the transportation of cylinders of this form it has been customary to carry a number of them in a permanently fixed position on a suitable type of freight car, in which each cylinder 10 is separately supported and braced in a quite rigid manner to prevent shifting of the load when the car is subjected to sudden shock. This necessitates a heavy and cumbersome framework which materially adds to the weight of the car, 15 and imparts to the load a high center of gravity.

It is an object of my invention to provide a car comparatively light in weight which, with the load, has the low center of gravity attainable by reducing to a minimum the amount of bracing framework required.

Another object is to eliminate entirely all rigid bracing mechanism, and provide means for transporting a plurality of cylinders in an easily demountable manner.

25 A further object is to provide a car having cushioning means thereon adapted to relieve lengthwise strain on the load due to sudden stopping and jolting of the car.

These and other objects are attained by providing, as a part of each individual cylinder, 30 means for interlocking the cylinders one with another, said means also cooperating with mechanism on the car body to restrain lengthwise movement of the entire load.

35 The advantages of my invention will be evident from a description of the accompanying drawings showing one modification thereof, wherein

Fig. 1 is a side elevation of a portion of a tank 40 car embodying the invention, with a small section broken away to show the cushioning means.

Fig. 2 is a view on the line II—II of Fig. 1.

Fig. 3 shows in detail the interlocking collar and the manner in which the collars engage.

45 Fig. 4 is a view of the collar end of the cylinders.

Reference numeral 1 indicates a cylinder having the conventional form of cylindrical body. Each end of the cylinder has a necked portion 50 provided with an enlarged beveled portion 2. Fitting snugly within this beveled portion and the slope of the neck, and rigidly attached to the neck, is the interlocking collar 3. In the form shown the collar is attached to only one end of 55 each cylinder. This collar has a grooved por-

tion 4 between two annular ribs 5 which are slightly larger in diameter than the body of the cylinder. The grooved portion 4 is slightly smaller in diameter than the body of the cylinder and is of such width as to engage the ribbed portion 5 of a similar collar on another cylinder when the two are placed side by side in the position shown in Figure 3. Small sections of the ribs 5 are slightly flattened at opposite sides, as shown in Figure 4, in order that two or more cylinders may 10 be placed in alignment with each other when desired and still have their body portions in contact. This feature is of importance in arranging the cylinders for shipment.

After placing a collar of this nature on one end of all cylinders ready for shipment, a multiple cylinder tank car may be built up in the manner shown in Figures 1 and 2. A car having a flat body member 6 is sufficiently long to accommodate two cylinder lengths and two complete piles 20 of twenty-one cylinders each. The cylinders are placed with the interlocking collars of the two piles toward each other in the center portion of the car body, and each group is supported and braced in the same manner. By arranging the 25 cylinders in a triangular pile with the upper cylinders setting in the interstices between each pair of lower cylinders it is comparatively easy to prevent their lateral movement. The weight of the cylinders alone tends to hold the upper ones 30 in place, and the side blocks 14 engaging the outside cylinders of the bottom row will act to laterally hold all of them in position.

The interlocking collars function primarily to restrain longitudinal movement of the cylinders. 35 It will be noted that the bottom row of cylinders is in alignment with each other and the groove in the collar of each cylinder engages with a slightly raised portion 8 of the member 7, extending laterally across the car body. The ribbed 40 portions of each collar engage the grooves 9 on either side of the strip 8. The second row of cylinders is set back slightly from the bottom row so that the collars of the two rows may interlock in the manner shown in Figure 3. The third 45 row is again set forward in vertical alignment with the bottom row. By thus vertically staggering the rows and placing each horizontal row of cylinders in alignment with each other, all of the cylinders are interlocked one with another and the entire pile is interlocked with the body 50 of the car. Each cylinder interlocks with one or more other cylinders with the exception of the two outside bottom ones of the triangle, and these each engage one upper cylinder and the 55

floor of the car. The collars lock at their top and bottom sections only, since it is necessary to flatten small portions of the ribs 5, as previously explained, to permit horizontal alignment of each 5 row of cylinders. This engagement of the collars is sufficient however to brace the entire load, since each collar is so constructed that the strain imposed thereon is transmitted to the body of the cylinder without setting up any material bending action in the neck of the cylinder.

The weight of a group of cylinders of this number acts to lock and hold the entire load, but it also imparts considerable momentum to the load in travel. In order to relieve the strain caused by 15 emergency stopping or other sudden jolting of the car, I prefer to cushion the section 7 of the car body carrying the locking strip 8 and grooves 9. The heavy coil springs 10 will serve this purpose, and are so arranged as to permit a limited 20 lengthwise movement of the load under severe shock. As an additional precaution the braces 11 may be provided which are anchored at one end to the sides of the car body and engage both 25 ends of the upper three cylinders through the yokes 12. These braces, pulling at an angle, prevent the upper cylinders from being jolted out of place, and they consist preferably of cables which have sufficient resiliency to permit the 30 above mentioned limited lengthwise movement of the pile against the cushioning springs 10.

The car body and its load arranged as described cooperate with each other to form a multiple cylinder tank car unit having a very low center of gravity, which, in conjunction with 35 the lack of absolutely rigid bracing mechanism, provides a car having easier and safer riding qualities than those heretofore used in similar transportation. Furthermore the entire cylinder load may be easily removed, whenever desired, by 40 loosening the angular bracing members 11.

It will be evident that the number of cylinders which may be carried in this manner on one car will vary with the size of the cylinder. While I prefer to arrange each group of cylinders in a 45 triangular form, they may also be arranged in other formations in which the interlocking means will be equally effective. The particular interlocking collar shown is attached as a separate piece to the cylinder, but means other than an attachable collar, which is formed as a unit with, or part of, the cylinder body may also be found suitable. Various other modifications in the embodiment shown and described may be made 50 without departing from the spirit of my invention.

I claim:

1. A multiple cylinder tank car comprising a flat body member; a plurality of cylinders on said body member, said cylinders being arranged 60 in a pile of triangular form with the upper cylinders resting in the interstices formed between pairs of lower cylinders; means on each of said cylinders adapted to directly interlock with similar means on an adjacent cylinder to prevent 65 relative longitudinal movement of the cylinders; means on the body member to prevent lateral movement of the cylinders; and means forming a part of the floor of the body member for engaging the interlocking means of the bottom row of said 70 cylinders to prevent longitudinal movement of the pile beyond certain limits, and means for cushioning the longitudinal movement of the cylinders in both directions.

2. A multiple cylinder tank car comprising a flat body member; a plurality of cylinders on said 75

body member; said cylinders being arranged in a pile of triangular form with the upper cylinders resting in the interstices formed between each pair of lower cylinders; a grooved collar on one end of each of said cylinders adapted to interlock with the collar on an adjacent cylinder to prevent relative longitudinal movement of the cylinders; side blocks on the body member to prevent lateral movement of the cylinders; a raised laterally extending ridge on the floor of said body member adapted to engage the grooved collars on the bottom row of cylinders to prevent longitudinal movement of the pile; and angularly disposed bracing members anchored at one end to the body member and engaging with cylinders at the top of the pile.

3. A multiple cylinder tank car comprising a flat body member; a plurality of cylinders on said body member; said cylinders being arranged in a triangular pile with the upper cylinders resting in the interstices formed between each pair of lower cylinders; a grooved collar on one end of each of said cylinders adapted to interlock with the collar on an adjacent cylinder to prevent relative longitudinal movement of the cylinders; side blocks on the body member engaging the two outside bottom cylinders to prevent lateral movement thereof; flexible angularly disposed bracing members anchored at one end to the body member and engaging both ends of the three top cylinders; a raised laterally extending ridge on the floor of said body member adapted to engage the grooved collars on the bottom row of cylinders to normally prevent longitudinal movement of the pile; and a cushioning means associated with said ridge to permit a limited longitudinal movement of the pile when the car is subjected to severe shock.

4. A fluid pressure container comprising a cylindrical body having a necked portion at the end thereof, and a collar on said necked portion, said collar having a groove therein and other portions permitting it to engage with a similar collar on another container placed in side by side relation therewith.

5. A fluid pressure cylinder having a necked portion at the end thereof, and a collar attached to said necked portion, said collar having an annular groove therein between two ribs whose outer periphery is of slightly greater diameter than the body of the cylinder, whereby the ribs may engage with the grooved portion of a similar collar on a cylinder placed adjacent thereto with the sides in contact.

6. A fluid pressure cylinder having a necked portion at the end and an interlocking collar on said necked portion, said collar having an annular groove therein between two ribs with an outer periphery slightly greater in diameter than the body of the cylinder and of such width as to permit them to engage with the grooved portion of a similar collar, whereby a plurality of cylinders carrying such collars may be piled lengthwise adjacent to one another and be interlocked at their ends to prevent relative longitudinal movement thereof.

7. A fluid pressure container comprising a cylindrical body having a removable collar thereon adapted to engage with a similar removable collar on another container placed in juxtaposition thereto, whereby a plurality of said containers will interlock one with another when arranged in a lengthwise adjacent position to prevent relative longitudinal movement thereof.

8. In combination, a plurality of cylinders and means for connecting them in lengthwise adjacent position in groups for shipment comprising collars securely connected with the cylinders and having parts interengaging with like parts of collars on other cylinders.

9. In combination, a plurality of cylinders and means for connecting them in lengthwise adjacent position in groups for shipment, comprising collars secured one to each cylinder and having circumferentially extending, spaced flanges

interengageable with similar flanges on other contiguous cylinders.

10. In combination a plurality of cylinders, means for connecting them in lengthwise adjacent position in groups for shipment comprising collars securely connected with the cylinders and having parts interengaging with like parts of collars on other cylinders, and means for yieldably securing a group of cylinders so connected to a vehicle.
